(57) **CLAIM**

We claim, the ornamental design for a vial, as shown and described.

DESCRIPTION

FIG. 1 is a top perspective view of a vial showing our new design;

FIG. 2 is a front elevational view of the vial of FIG. 1; FIG. 3 is a side elevational view of the vial of FIG. 1; FIG. 4 is another side elevational view of the vial of FIG. 1; FIG. 5 is a top plan view of the vial of FIG. 1;

FIG. 6 is a rear elevational view of the vial of FIG. 1; and, FIG. 7 is a bottom plan view of the vial of FIG. 1. The broken lines shown in the drawing figures are for illustrative purposes only and form no part of the claimed design.

1 Claim, 4 Drawing Sheets
